DESIGN FOR A BAKING PAN

Joseph G. Jackson, Oak Park, Ill., assignor to
The Edward Katzinger Company, Chicago, Ill.,
a corporation of Illinois

Application January 2, 1937, Serial No. 66,868

Term of patent 14 years

To all whom it may concern:

Be it known that I, Joseph G. Jackson, a citizen of the United States, residing at Oak Park, in the county of Cook and State of Illinois, have invented a new, original, and ornamental Design for a Baking Pan, of which the following is a specification, reference being had to the accompanying drawing, forming a part thereof.

Fig. 1 is a plan view of a baking pan showing my new design, the bottom and walls thereof being ornamented throughout the entire area thereof by the use of a series of ridges and depressions making an angle with a second series of ridges and depressions so as to give the impression of a plurality of rectangular shaped areas as defined by the shaded detail portion. In lieu of shaded detail throughout the figure, a crossed-line background has been applied to

represent a continuation of the ridges and depressions defining said rectangular shaped areas.

Fig. 2 is an enlarged sectional view taken on line 2—2 of Fig. 1 and includes an elevational view of the pan side wall having a shaded detail portion. As in Fig. 1, in lieu of shaded detail throughout the figure, a crossed-line background has been applied to represent a continuation of the ridges and depressions defining the rectangular shaped areas.

Fig. 3 is an enlarged fragmentary detail view.

The characteristic feature of this design resides in the ornamental bottom and walls as shown.

I claim:

The ornamental design for a baking pan, as shown and described.

JOSEPH G. JACKSON.
